DESIGN FOR A GAME BOARD

Estelle Wald, New York, N. Y.

Application January 24, 1940, Serial No. 89,676

Term of patent 3½ years

To all whom it may concern:

Be it known that I, Estelle Wald, a citizen of the United States, residing at 225 West 106th Street, Borough of Manhattan, city, county, and State of New York, whose post office address is the same, have invented a new, original, and ornamental Design for a Game Board, of which the following is a specification, reference being had to the accompanying drawing, forming a part thereof.

In the drawing:

I claim:

The ornamental design for a game board, as shown.

ESTELLE WALD.
